UNITED STATES PATENT OFFICE

CURT O. WINTER, OF SAYLESVILLE, RHODE ISLAND

DESIGN FOR A SAFETY RAZOR

Application filed January 19, 1933. Serial No. 46,884. Term of patent 7 years.

To all whom it may concern:

Be it known that I, CURT O. WINTER, a citizen of the United States, residing at Saylesville, in the county of Providence and State of Rhode Island, have invented a new, original, and ornamental Design for a Safety Razor, of which the following is a specification, reference being had to the accompanying drawing, forming part thereof.

I claim:

The ornamental design for a safety razor, as shown.

In testimony whereof I have signed my name to this specification.

CURT O. WINTER.
